CLAIM

The ornamental design for a frets device for a handheld game, as shown and described.

DESCRIPTION

FIG. 1 is a perspective view of a fret device for a handheld game showing our new design;

FIG. 2 is a bottom plan view thereof;

FIG. 3 is a left side elevational view thereof, the right side elevational view being a mirror image thereof;

FIG. 4 is a top plan view thereof;

FIG. 5 is a front elevational view thereof; and,

FIG. 6 is a rear elevational view thereof.

The broken lines environment of the design is for illustrative purpose only and forms no part of the claimed design.
